OIL BURNING BOILER

Marco Casale, New York, N. Y., assignor to Casmark Corporation, New York, N. Y.

Application March 30, 1936, Serial No. 71,707

3 Claims. (Cl. 122—368)

This invention relates to boilers and is directed to a boiler provided with a gun type or pressure oil burner.

An object of this invention is to provide a highly improved unitary fire pit auxiliary boiler of the character described, so constructed as to permit ready installation within the fire pits of existing boiler furnaces of various sizes, and connection to the main boiler, to greatly increase the efficiency and reduce loss of heat.

A further object of this invention is to provide a boiler of the character described made of a single casting of cast steel or iron so constructed as to accommodate any gun type or pressure oil burner and having bottom, side, front and rear double walls forming a single chamber containing water directly receiving the flame from the burner to quickly heat the same without substantial loss of heat.

Another object of this invention is to provide an auxiliary boiler of the character described having means to collect oil drippings, and provided with an additional section constituting a combined chamber and flame deflector which may be readily added or removed depending upon the steam requirements.

Yet another object of this invention is to provide a compact and durable auxiliary boiler of the character described which may be incorporated into new boilers or installed in low pressure steam, hot water or high pressure steam boilers now existing, which shall be relatively inexpensive to construct and install and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a side elevational view of a boiler provided with an auxiliary boiler embodying the invention, with parts broken away to show the interior construction,

Fig. 2 is a cross-sectional view taken on line 2—2 of Fig. 1,

Fig. 3 is a perspective view of my improved auxiliary boiler removed from the furnace,

Fig. 4 is a perspective view of a modified form of auxiliary boiler; and

Fig. 5 is an enlarged cross-sectional view taken on line 5—5 of Fig. 4.

Referring now in detail to the drawing, 10 designates a steam or hot water boiler or furnace provided with an auxiliary boiler embodying the invention. The boiler 10 rests upon a cement or concrete floor 11 and comprises generally of a lower base or fire pit portion 14, a cylindrical water jacketed portion 15, and a top portion 16 likewise provided with a water jacket. The door 10 17 of the furnace is in the portion 15 thereof, and the bottom portion 14 has a flanged opening 19 receiving the inwardly projecting, horizontal nozzle 20 of the oil burner, which may be of any gun or oil pressure type.

An inlet pipe 22 is connected to the bottom end of the portion 15, as at 23, to feed cold water to the boiler. An outlet pipe 25 connected to the top of the boiler, serves as an outlet for the heated water or steam.

The auxiliary boiler 26 embodying the invention is located within the fire pit or bottom part of the boiler and rests on the floor 11. Said boiler is of generally prismatic shape and is preferably made of a single casting, either cast iron or cast steel. The same comprises a bottom portion 27, a rear portion 28, a front portion 29, and left and right side portions 30 and 31. Said portions have double walls to provide a single box like chamber for water. The bottom wall has a central through opening 32 adjacent the front portion for the purpose hereinafter appearing.

The front wall 29 has a central cut out 34 at the top aligned with the flanged opening 19, to accommodate the end of the burner nozzle 20. Preferably the upper edge of the front, rear and side portions of the boiler 26 is of a higher level than the nozzle 20 so that the flames from the latter are directed into the hollow of said boiler.

The upper edge of the front wall 29, on opposite sides of the cut out 34, has an inwardly extending hollow lip 29a forming a ledge to extend the top front portion of the boiler whereby the boiler may be used in fire pits of various sizes.

The outer wall of front portion 29 may be provided with a clean out plug 36. The outer wall of side portion 31 is provided with a pair of upper and lower nipples 38 and 39. The outer wall of the other side wall 30 has a nipple 40 adjacent the top of said wall. A pipe 41 may interconnect the bottom of jacket portion 15 with the lower nipple 39, said pipe extending through a suitable opening 42 in the portion 14 of the boiler. Another pipe 43 interconnects the nipple 40 with the top portion 16 of the boiler 10, said pipe pass-

ing through a suitable opening 44 in the base of the furnace. The nipple 38 may be closed by a plug.

The top walls of side portions 29, 30 may also 5 be provided with screw threaded openings 45, 46 plugged by plugs 45a, 46a, for the purpose hereinafter appearing.

It will now be understood that drippings from 10 the burner nozzle will collect in the opening 32, and any suitable absorbent material may be placed in said opening to absorb the dripped oil.

If desired, the nipple 40 may be plugged and 15 the pipe 43 connected to the nipple 38: Thus the pipe 43 may be located on either side of the boiler.

It will now be understood that water is fed 20 through inlet pipe 22 to the water jacket 15. Also from said jacket water passes to the bottom of the auxiliary boiler 26 through pipe 41. The heated water or steam passes from boiler 26 to 25 the water jacket 16 through pipe 43 and mixes with the steam or water heated within jacket 15, thence passing to the outlet pipe 25.

In Figs. 4 and 5 is illustrated a modified form 25 of my invention. In said figures is shown an auxiliary boiler 26. The plugs 45a, 46a are removed however and upstanding pipes 50, 51 are screwed to the openings 45, 46. Mounted on said pipes is an additional section 53 comprising a hollow, 30 horizontal ribbed jacket provided on the under side thereof with openings to which the upper ends of the pipes 50, 51 are screwed. Said jacket or section 53 is preferably provided with a pair of plugged openings 54, 55 on the top surface 35 thereof. When the additional section 53 is utilized, the nipples 38 and 40 are plugged and the pipe 43 is screwed either to the one or the other of the openings 54, 55 depending upon which side of the boiler it is desired to locate said pipe.

40 It will thus be seen that there is provided a device in which the several objects of this invention are achieved, and which is well adapted to meet the condition of practical use.

45 As various embodiments might be made of the above invention, and as various changes might be made in the embodiments above set forth, it is to be understood that all matter herein set forth or shown in the accompanying drawing is to be interpreted as illustrative and not in a limiting sense.

Having thus set forth and disclosed the nature of this invention, what is claimed is:

1. An auxiliary boiler adapted to be received in the fire pit of a furnace comprising a single casting of substantially rectangular shape providing 5 a front portion, side portions and a bottom portion, said portions being double walled to form a single water circulating chamber, said bottom portion having a centrally located opening, said front portion being recessed, the opening in said bottom portion constituting an oil sump, the recess in said front portion being arranged to receive a burner nozzle, and a combined hollow auxiliary chamber and flame deflector communicating with the side portions of 10 said water circulating chamber and extending upwardly therefrom.

2. An auxiliary boiler adapted to be received in the fire pit of a furnace comprising a single casting of substantially rectangular shape providing 20 a front portion, side portions and a bottom portion, said portions being double walled to form a single water circulating chamber, said bottom portion having a centrally located opening, said front portion being recessed, the opening in said 25 bottom portion constituting an oil sump, the recess in said front portion being arranged to receive a burner nozzle, a combined hollow auxiliary chamber and flame deflector, a pair of hollow pipe members each communicating with a 30 side portion and with the combined hollow auxiliary chamber and flame deflector.

3. An auxiliary boiler adapted to be received in the fire pit of a furnace comprising a single casting of substantially rectangular shape providing a front portion, side portions and a bottom portion, said portions being double walled to form a single water circulating chamber, said bottom portion having a centrally located opening, said front portion being recessed, the opening in said 40 bottom portion constituting an oil sump, the recess in said front portion being arranged to receive a burner nozzle, a combined hollow auxiliary chamber and flame deflector comprising a ribbed jacket horizontally positioned above said 45 single water circulating chamber, said combined chamber and flame deflector communicating with the side portions of said circulating chamber and extending upwardly therefrom.
